Application September 7, 1933, Serial No. 688,483

3 Claims. (Cl. 200—19)

This invention relates to improvements in a distributor cap for the ignition timing mechanism of an internal combustion engine.

An object of the invention is to provide a cap 5 of glass or other good transparent dielectric through which the sparking of the distributor contacts may be examined during operation.

A further object of the invention is to provide a distributor cap in which all the contact points 10 are individually removable and replaceable.

A further object of the invention is to provide a distributor cap formed solely of glass or the like and adapted to receive removable unitary contact points and cable receiving sockets that 15 may be locked in the glass cap by the insertion therein of the usual cable ends.

A still further object of the invention is to provide a distributor cap of glass or the like of the nature and for the purposes set forth that is 20 characterized by structural simplicity, durability and low cost of production, being thereby rendered commercially desirable.

To the accomplishment of these and related objects as shall become apparent as the description proceeds, the invention resides in the construction, combination and arrangement of parts as shall be hereinafter more fully described, illustrated in the accompanying drawing and pointed out in the claims hereunto appended.

30 The invention will be best understood and can be more clearly described when reference is had to the drawing forming a part of this disclosure, wherein like characters indicate like parts throughout the several views.

35 In the drawing:—

Figure 1 is a plan view of my improved distributor cap;

Figure 2 is a vertical section thereof, as taken on the line 2—2;

40 Figure 3 is a perspective elevation of one of the replaceable combined cable-receiving socket and contact points; and

Figure 4 is a detail vertical section of a modified form of central contact.

45 Much motor trouble is occasioned by faulty operation of the timing and distributing mechanism of the electrical sparking equipment in the modern internal combustion engine. This is partly due to the difficulty of locating and identifying trouble of this nature; a "short" often occurring in what seems to be a perfect distributor cap. And furthermore though condenser trouble manifests itself by a red spark between the commutator arm and the fixed contacts it is undis-
50 cernible because of the opaque caps in use and

can only be checked up by use of special and expensive condenser testing apparatus. In addition to this some distributor caps must be discarded because one or two of the contact points have become worn or burnt although the body of the cap and the rest of the contacts are still in condition to give years of service.

In this invention, the distributor cap 5 of generally conventional design, and adapted for use on standard timers and distributors, is of transparent glass or the like and so is a perfect dielectric with no possibility of "shorts" across or through the cap itself.

The cap is provided with a central and surrounding concentric row of circumferentially spaced pockets 6 moulded in the thick top of the glass. The top or neck of each of these pockets 6 is round as is also the interior chamber 8 that opens out inside, joining the neck 7 with a square shoulder 9. The bottom of the pocket 6 is formed 20 as an annular seat 10, coaxial with and of the same diameter as the neck 7, from centrally of which a small circular bore 11 extends through to the hollow underside 12 of the cap.

A usual cup-fitting flanged lower rim 13 and 25 a pair of diametrically opposite spring clip receiving notches 14 on the side walls complete the glass cap proper. For insertion in the circumferential row of pockets 6, removable cable-receiving sockets 15 are provided that are each formed 30 as a cylinder of a diameter to slide snugly in the neck 7 and annular seat 10; the bottom 16 of the cylinder 15 is closed and provided with a coaxial depending stud 17 that projects through the bore 11 and substantially enters the hollow 35 underside 12 of the cap. These cylinders 15 are slotted vertically down from their open tops for the greater part of their length dividing the same circumferentially into a plurality of vertical spring fingers 18. Near the top of the cylinder 40 these fingers 18 are bent angularly outwardly and then inwardly, beyond the normal circumference, providing thereby an exterior annular bulge or ring 19 and a constricted or smaller neck 20. The top rim 21 of this constricted neck 45 20 is then terminally rolled outwards.

The size, shape and proportion of these removable contact-point-cable-receiving inserts 15 is such that the stud 17 extends through the thick 50 glass top of the cap 5 and enters the hollow underside thereof the required distance and the closed bottom 16 and lower end of the cylinder 15 seats snugly in the annular recess 10 when the rest of the cylindrical insert is contained 55

within the chamber 8, the spring fingers 18 flexing inwards to allow the bulge ring 19 through the neck 7 of the pocket and then expanding to clampingly hold the cylinder in the chamber 9 by pressing outwards with the inturned upper angular side of the bulge against the shoulder 9 at the bottom of the pocket's neck.

The cable ends are then pushed into the cylinders 15 and fitting snugly therein are gripped tightly by the constricted top rim 21 thereof and substantially occupying the whole of the cylinder anchors the latter tightly and securely in its pocket in the cap.

The central cylinder and contact shown, is of identical form with those in the surrounding ring except the stud 22 is of larger diameter (its accommodating bore being sized accordingly) and is centrally recessed to receive a carbon 23.

From the foregoing description taken in connection with the accompanying drawing, it will be manifest that a distributor cap is provided that will fulfill all the necessary requirements of such a device, but as many changes could be made in the above description and many apparently widely different embodiments of the invention may be constructed within the scope of the appended claims without departing from the spirit or scope thereof, it is intended that all matters contained in the said accompanying specification and draw-

ing, shall be interpreted as illustrative and not in a limitative or restrictive sense.

Having thus described the invention, what is claimed as new is:—

1. A distributor cap of glass or the like having pockets in the top thereof, openings through said cap from the bottom of said pockets and replaceable contact points in said pockets adapted to be locked therein by the insertion of cable ends.

2. A distributor cap of glass or other transparent dielectric having a central and surrounding row of pockets therein, narrowed necks at the top of said pockets, coaxial seats of like diameter in the bottom of said pockets, bores through said cap from the bottom of said pockets and removable contact points adapted to seat snugly and securely in said pockets.

3. A distributor cap of glass or other transparent dielectric having a central and surrounding row of pockets therein, narrowed necks at the top of said pockets, coaxial seats of like diameter in the bottom of said pockets, bores through said cap from the bottom of said pockets, cylindrical inserts in said pockets adapted to clamp against the narrowed necks thereof and contact points depending from the bottom of said cylinders adapted to extend through the bores in the bottom of said pockets.

WILLIAM SHERMAN. [L. S.]
